UNITED STATES PATENT OFFICE.

WILLIAM KRAFVE, OF FALL RIVER, MASSACHUSETTS.

MUFFLER.

1,396,583.

Specification of Letters Patent.

Patented Nov. 8, 1921.

Application filed May 8, 1920. Serial No. 379,757.

To all whom it may concern:

Be it known that I, WILLIAM KRAFVE, a citizen of the United States, residing at Fall River, in the county of Bristol and State of Massachusetts, have invented new and useful Improvements in Mufflers, of which the following is a specification.

This invention relates to certain new and useful improvements in mufflers, and pertains to mufflers for use in connection with internal combustion engines.

The primary object of the invention is to provide a muffler which is composed of but two castings suitably connected so as to be capable of easy and quick assemblage and disconnection thereby to allow of cleaning, and to further provide a muffler which is effective in operation and highly efficient for the purpose.

Further, the invention aims to provide a muffler in which the exhaust gases are caused to travel in a spiral path prior to egressing.

Still further and other objects will be later set forth and manifested in the course of the following description.

In the drawings:

Figure 1, is a side elevation of the invention;

Fig. 2 is a section on line 2—2 of Fig. 1; Fig. 3, is a top plan view of the interior of one half of the device and

Fig. 4, is a bottom plan view of the interior of the other half.

In proceeding in accordance with the present invention, two castings are employed one of which 1, having an L-connection 2, of tubular form providing either an inlet or an outlet as desired, which connection extends outwardly from the outer wall of the casting 1, and communicates with the center of the interior of the casting. The casting 1, has a preferably circular marginal wall 3 and a peripheral connection 4, extending outwardly from the wall 3. On its interior, the casting is formed with a spiral wall or partition 5, forming a spiral passage for the exhaust gases, the wall 5, terminating at one end at one side of connection 4, and at its opposite end in partial surrounding relation to the connection 2, as indicated at 6, in Figs. 2 and 4. The upper edges of the wall 3 and the spiral wall 5, are convex in form as depicted in Fig. 2 at 7 for the purpose of nesting in

the concave free edges 8, of the spiral wall 5, and marginal wall 10, of the complementary casting 11. The casting 11, is a duplicate of the casting 1, excepting as to the connection 2, which latter is omitted in the casting 11. The casting 11 further has a connection 12, which is complementary to the connection 4, of the other casting 1, the two connections mating to form a completely tubular inlet or outlet as desired and as depicted in Fig. 2, of the drawings.

The two castings are held together by means of bolts 13, having nuts 14, which bolts pass through suitable openings formed for their reception in the two castings. The castings further each have a base portion 15, which latter conjointly form a base for supporting the entire device in position.

In operation, the exhaust gases from the engine may be admitted to the muffler either at the center thereof by conducting the gases to connection 2, or the gases may be admitted to the periphery of the muffler by conducting such gases to the connection formed by the parts 4 and 12. In either instance, the gases are caused to pursue a spiral path of travel from the point of ingress to the point of egress, whereby the gases are effectually muffled or silenced.

It will further be seen that by removing the nuts 14 the two castings may be separated and cleaned and then easily reassembled.

Having thus described my invention, what I claim as new and desire to secure by Letters Patent is:—

1. In a muffler, a pair of castings, each having a flat wall and a substantially circular marginal wall, a spiral wall in each casting connected to the flat wall thereof, a connection extending from the flat wall of one casting and communicating with the center of the interior of the casting, complementary connections leading peripherally of the marginal walls of the castings and connecting to the outer end of the spiral passage, the spiral walls having concave and convex edges nested one within the other, fastening bolts passed through the two castings to secure same together, and complementary base portions extending peripherally from the castings, said spiral walls being each continuous and at one end leading from one side of the peripheral con-

nections, and at the opposite end terminating in partial surrounding relation to the center connections.

2. In a muffler, a pair of castings having 5 central inlet and peripheral outlet connections, each casting having a spiral wall forming a spiral passage, said walls having abutting and nesting concave and convex edges, and fastening means passed through 10 the castings for securing same together said spiral walls being each continuous and at one end leading from one side of the peripheral connections and at the opposite end terminating in partial surrounding relation 15 to the center connections.
3. In a muffler, two castings each having a spiral wall forming a spiral passage, inter-engaging means between the adjacent edges of the adjacent walls, a central inlet and 20 a peripheral outlet connected to the respective ends of the spiral passage, and fastening means for securing the castings together said spiral walls being each continuous and at one end leading from one side of the

peripheral connections and at the opposite 25 end terminating in partial surrounding relation to the center connections.

4. In a muffler, a pair of castings each having a spiral wall forming a spiral passage, said walls being in abutting engagement at their free edges, fastening means 30 to hold the sections together, and a central inlet and a peripheral outlet connection extending from the respective ends of the spiral passage, said spiral walls being each 35 continuous and at one end leading from one side of the peripheral connections and at the opposite end terminating in partial surrounding relation to the center connections.

In testimony whereof I have signed my name to this specification in the presence of two subscribing witnesses.

WILLIAM KRAFVE.
